Chicago, Ill.

Application January 14, 1938, Serial No. 184,958

7 Claims. (Cl. 40—34)

This invention relates to improvements in or pertaining to display apparatus and the like and has for its object: first, to provide a novel and attractive display which will attract attention, 5 and second, to provide a display, the face of which can be changed easily and quickly.

The invention concerns display apparatus and the like of the type comprising a face or base and a plurality of rotatable display elements associated with it carrying all or part of the matter to be displayed. Heretofore, with display apparatus of this type, the face or base and rotatable display elements have been made an integral part of the apparatus and it has been 10 necessary to paint, draw, stamp or otherwise affix the matter to be displayed directly upon said face or base. This made the changing of display matter upon the apparatus a difficult and costly procedure. According to the present 15 invention, the face or base and the rotatable display elements are made from the poster, bill, card, placard, sign, and the like which is to be actuated and upon which the matter to be displayed has been printed, lithographed, painted, 20 carved, embossed, engraved, or otherwise impressed.

With the above and other objects in view, the invention consists of certain novel details of construction and combinations of parts hereinafter 30 fully described and claimed, it being understood that various modifications may be resorted to without departing from the spirit and scope of the invention as claimed hereinafter.

For the purpose of illustration only, and in no 35 way intended to limit the scope of the invention, an embodiment of the invention is illustrated in the accompanying drawings forming a part of this specification, in the several views of which like parts are designated by similar characters 40 and in which—

Figure 1 is an isometric view of the front of a display apparatus according to the invention,

Figure 2 is a section on an enlarged scale on the line 2—2 of Figure 1,

Figure 3 is a rear elevation of a display apparatus according to the invention, and

Figure 4 is a view similar to that of Figure 3 with certain elements thereof removed.

Referring now to Figures 1 and 2 of the drawings, a poster to be actuated 1, with circular sections 3 removed therefrom as illustrated, is affixed to a framework 4. Corresponding circular sections 5, somewhat larger than said removed sections 3, are cut from another and identical 50 poster and are so placed behind the correspond-

ing openings in poster 1 and in intelligible register therewith, that they, in combination with said poster 1, present an appearance similar to that of said poster before the aforesaid sections were removed therefrom. A circular disk 7 (see 5 also Figure 4) is centered behind each circular section 5 and affixed thereto. A crankshaft 6 is attached to the center of each disk 7 by means of a pin 8 which runs through a hole 9 in the terminal of said crankshaft 6 and rests in a slot 10 in the face of said disk 7. Each crankshaft 6 runs through a bushing 11 in cross member 12 (see also Figures 3 and 4). A crank pin 13 is rotated around each crankshaft 6 by means of a crank plate 14 (see also Figures 3 and 4) 15 which engages all of said crank pins 13 and moves in a circulatory motion in a radius equal to the length of the crank webs 15 thereby causing all of said crank pins 13 to rotate about their respective crankshafts and causing also the rotation of the aforesaid disks 7. Intermittent circulatory motion is given crank plate 14 by the rotation of worm gear 16 Figures 2 and 3.

Worm gear 16 engages crank plate 14 by means of a pin 17, Figures 2 and 3, fastened to said worm gear 16 a distance from the center of said worm gear equal to the length of the crank webs 15, said pin 17 running in bushed bearing 18 in the aforesaid crank plate 14. In order that the aforementioned worm gear 16 may pause once 30 each rotation and thus impart an intermittent circulatory motion to the crank plate 14, the following construction has been used.

Referring to Figure 3, dotted lines 19, 20, and 35 21 delineate segment 23 which has been removed from the circumference of worm gear 16. Another segment 24, having the same radius and other gear characteristics as said removed segment, but having a larger arc, is pivoted at the center 25 of worm gear 16 and so placed adjacent 40 that it is free to move in a plane parallel to the plane of motion of said worm gear as the aforementioned worm gear moves in the direction indicated in Figure 3. As worm gear 16 rotates, pin 26 engages segment 24, causing said segment to move with the aforesaid worm gear 16. When that part of worm gear 16 from which segment 23 has been removed reaches a point nearest worm 27, motion of said worm gear ceases and segment 24, having been carried around in 50 its rotation with worm gear 16 by pin 26, engages with worm 27 and continues its rotation. Worm gear 16 remains stopped until the rotation of segment 24 causes said segment to engage pin 28 at which point worm gear 16 is forced to con- 55

tinue its rotation with segment 24. When segment 24 is engaged with either pin 26 or pin 28, the teeth of segment 24 and the teeth of worm gear 16 coincide at those points where part of 5 said segment 24 overlaps the part of worm gear 16 from which segment 23 has been removed so that worm 27 engages both worm gear 16 and segment 24 simultaneously at those overlapping points. When segment 24, in its rotation, passes 10 worm 27 a sufficient distance, spring 29 forces the aforesaid segment to reengage pin 26. Worm 27 is driven by an electric motor 30 through a shaft 31.

We are aware that prior to our invention display apparatus have been made with stationary display sections and rotatable display sections. We therefore do not claim such a combination broadly, but

We claim:

20 1. In a display apparatus having a continuous display front made up of stationary display sections and rotatable display sections, the combination of a plurality of said rotatable display sections each of said rotatable display sections 25 mounted on a shaft, a hole through said shaft parallel to the plane of rotation of said shaft and perpendicular to its length, a pin longer than the diameter of said shaft, said pin reposing in the said hole in said shaft, a recession in the 30 face of each aforesaid rotatable display section in which the ends of the aforesaid pin repose and driving means for rotating said rotatable display sections.

2. In a display apparatus having a continuous display front made up of stationary display and rotatable display sections, the combination of a plurality of said rotatable display sections, each of said rotatable display sections being mounted on the crank shaft of a crank, the 35 crank pin of said crank engaging a crank plate, said crank plate engaging all of the plurality of crank pins aforesaid and moving in a circulatory motion in a plane parallel to the plane of the crank webs of the aforesaid crank shafts, the radius of said circulatory motion being equal 40 to the length of the webs of the aforesaid crank shafts, said circulatory motion being imparted to each of the plurality of aforesaid cranks through the crank pins of each and causing each 45 of the aforementioned rotatable display sections to rotate and driving means for driving said crank plate.

3. In a display apparatus having stationary sections and movable sections said movable sections pausing at intervals in their motion, the combination of a drive gear being driven by the power mechanism of said display apparatus and a driven gear transmitting the motion of said drive gear to the movable sections of the aforesaid display apparatus, said driven gear having a segment removed from its circumference, another segment having the same radius and similar gear characteristics as the said driven gear and having an arc larger than the arc of the 55 aforesaid removed segment being centered on

the shaft upon which said driven gear is centered in such a manner that the arc of said segment coincides with the circumference of said driven gear, said segment being free to move only in a plane parallel to the plane of motion 5 of the said driven gear, said segment being so placed on the said shaft adjacent to said driven gear that said segment rotates with said driven gear, a stop affixed to said driven gear in such a manner that when the portion of said driven gear from which the aforesaid segment has been removed, reaches a point of engagement 10 with the aforesaid drive gear and the rotation of the said driven gear ceased said added segment continues its rotation being engaged with said drive gear the face of said drive gear being sufficiently large to engage both the driven gear and the said added segment simultaneously, the aforesaid stop engages the said added segment causing the said driven gear to continue 15 its rotation with the said added segment, a spring to cause said added segment to return to its original position and a stop to hold said added segment in its original relative position with said driven gear until said driven gear rotates to 20 such a position that its removed section from which the aforesaid segment has been removed again engages the aforesaid drive gear.

4. In a display apparatus having a plurality of rotatable display elements, in combination 30 with said plurality of rotatable display elements, a plurality of cranks, equal in number to said plurality of display elements, each of said cranks engaging each of said display elements, and a crank plate engaging each of said cranks at a 35 point on said crank plate which bears the same spaced relationship to every other point of engagement on said crank plate as each of the crank shafts of the aforesaid cranks bears to every other crank shaft of the aforesaid cranks, 40 so that an interrupted circulatory motion imparted to the crank plate aforesaid is transmitted to each of the aforesaid plurality of rotatable display elements.

5. The combination of a crank plate as described in claim 4 with driving means whereby a circulatory motion is imparted to said crank plate.

6. In a display apparatus of the type described, the combination of a drive gear, a driven gear having teeth removed from a section thereof, a gear segment having the same radius and similar gear characteristics as the said driven gear and movably engaged in juxtaposition with said driven gear, a stop limiting the motion of the aforesaid segment relative to said driven gear, and means to return said segment to a given position relative to said driven gear when, through engagement with the aforesaid drive gear it has 60 been caused to move therefrom.

7. The combination described in claim 6 and driving means.
